UNITED STATES PATENT OFFICE

1,923,330

APPARATUS FOR BURNING FUELS

Webster I. Sallee, Cleveland, Ohio

Original application February 19, 1930, Serial No. 429,519. Divided and this application February 2, 1931. Serial No. 512,766

13 Claims. (Cl. 158—4)

This invention relates to an apparatus for burning liquid fuels such as low grade oils and tars efficiently, permitting the use of such fuels in sand driers, metal treating furnaces and the like, and is in the nature of a divisional application of my copending application Ser. No. 411,279, filed December 3, 1929 and Serial No. 429,519, filed February 19, 1930.

Effective combustion of such fuels requires that the oil be atomized, thoroughly mixed with a conveying medium, and burned before the globules have settled out from the mixture.

The methods now employed contemplate atomizing the fuel by a fuel gun or ejector which is arranged to discharge directly into the combustion chamber of a drier or furnace, depending on the radiant heat from the relatively large combustion chamber to vaporize and ignite the fuel.

Incomplete and inefficient combustion of the fuel results from these methods, causing carbonaceous deposits on the walls of the combustion chamber and loss of fuel due to suspended carbon and combustible gases passing out of the furnace with the products of combustion.

In sand driers and heating equipment in which the products of combustion come in contact with the material being treated, a clean flame and clean products of combustion are necessary.

It is therefore an object of my invention to reduce the costs of heating with liquid fuels by obtaining efficient combustion thereof and effective application of the heat obtained.

Another object of my invention is to produce a clean flame and eliminate the necessity for expensive stacks, and accomplish these results by the use of relatively inexpensive and easily obtainable equipment.

Another object of my invention is to provide an apparatus for burning liquid fuels which, even when completely cold, may be heated to a temperature sufficient for efficient operation within a very few minutes, thus permitting closing down out of working hours and eliminating the necessity of continuous heating or operation.

More specific objects of my invention include efficient production and effective control of heat from liquid fuels through a very wide range of volumes and temperatures.

Another specific object of my invention is to eliminate destructive concentration of heat on any part of the combustion chamber of a furnace or drier and to eliminate large radiation losses, by obtaining combustion evenly distributed over the most effective areas.

Another object is to preheat the fuel econom-

ically and control the size and shape of the flame.

Other objects and advantages of my invention will become apparent from the following description, in which reference is made to the drawings by the use of numerals.

In the drawings—

Fig. 1 is a side elevation of an apparatus suitable for carrying out the method of my invention, portions being shown in section for clearness.

Fig. 2 is an end elevation of the apparatus illustrated in Fig. 1.

Fig. 3 is an enlarged longitudinal sectional view of the oil atomizing gun and register illustrated in Figs. 1 and 2.

My process contemplates vaporization and partial combustion of an intimate mixture of air and oil by radiant heat, while the mixture is retained centrally of an enveloping quantity of air under pressure, the movement of the burning and vaporized oil and the enveloping air stream into a second enveloping air stream, wherein combustion is completed.

An apparatus which I have found efficient for carrying out this process includes a primary vaporizing chamber 1, closed at one end by a plate 2 having an opening to receive an air register 3, in which is mounted an oil atomizing gun 4 adapted to discharge a stream of atomized fuel into the chamber 1. The other end of this vaporizing chamber is contracted to form a cone-like head 5 and a nozzle 6, through which the heating media of the vaporizing chamber 1 may pass through a suitable port 7 into a combustion chamber of a furnace or drier.

The vaporizing chamber 1 is preferably a cylindrical shell, lined with refractory material, such as fire brick 8, and is relatively small in comparison to the furnace or drier to be heated. At a very moderate cost it may be lined with a high quality refractory and covered with asbestos or other insulating material. Thus high temperatures sufficient to cause almost instantaneous vaporization of low grade oils are brought in closer proximity to the stream of atomized fuel and damage to the apparatus from high temperature as well as heat losses by radiation are eliminated.

To introduce air and a spray of atomized oil into this chamber, the oil gun and air register fully described in Letters Patent of the United States No. 1,680,455, with certain modifications to meet my requirements, have proven satisfactory and are here shown for purposes of illustration. Any efficient atomizing gun may be used however.

As there described, the oil gun consists of a hollow casing 10, in which is mounted a spinner or cup 11, rotatable about a hollow shaft 12 on suitable bearings 13. An air turbine 14 is provided on the spinner to rotate it at high velocity as air is forced into the casing 10 from a fan or pump 15 through a conduit 16. The volume of air supplied is controlled by a valve 17. Oil is caused to flow from a reservoir to a pump 18, which forces it under low pressure through a conduit 19 passing into the casing 10 and joining the hollow shaft 12 through which the oil is discharged into the inside of the spinner 11. The spinner 11 imparts a rotary motion to the oil and discharges it in the form of a whirling sheet, conical in form. In the discharge end of the spinner 11 are a number of inturned teeth which strike the oil as it is thrown out of the spinner, imparting additional rotary motion thereto, and mechanically breaking the oil into a spray of small globules.

The air stream, after passing the turbine 14, passes out of the casing 10 between the casing and the spinner 11. Vanes 20 are provided within the casing near the discharge end to cause the air stream to leave the casing with a spiral motion, the direction of rotation being opposite to that of the oil stream so that the oil strikes the air at an abrupt angle, and insures more complete atomization and mixture.

As described in said patent, additional air is supplied through an air register 3. Radial vanes 21 mounted on rocker shafts 22 in the register 3, are provided to control the shape of the air stream passing out of the register. The rocker shafts 22 are pivotally mounted in a collar 23 about the gun casing 10 at their inner ends. The outer ends pass through openings in the register casing and are bent over to engage notches in a ring 24 loosely mounted on and rotatable about the register casing. By rotating the ring 24, the rocker shafts 22 rotate about their axes concurrently, changing the angle of the vanes 21 with respect to their open positions, which are parallel to the axis of the register.

In the patented structure, the volume of air drawn through the register 3 is controlled by an end plate such as the plate 25 which is slideable axially of the register on supporting rods 26 to increase or decrease the opening between the end plate and register.

In order to adapt this patented structure for my purpose, I use longer supporting rods 26 and increase the length of the casing 10 of the oil gun 4 and move the end plate 25 to its withdrawn position on the longer rods, as illustrated in Figs. 1 and 3 herein, and there secure it. Between the end plate 25 and the register 3 I install a sealed even pressure chamber 30 opening into the register 3, and control the volume of air passed therethrough into the register in a different manner, as will later be described. Air under pressure is supplied into the even pressure chamber by a fan 31, through a suitable conduit 32. A number of shutters 33 are provided at the entrance of the even pressure chamber 3 to control the volume of air entering it. These shutters may be provided with rocker shafts 34 extending through the walls of the even pressure chamber and bent over at their outer ends to engage notches in slideable lever 35, the movement of which changes the size of the air passage into the even pressure chamber by changing concurrently the angular position of the shutters.

As shown, it is desirable to make the even pressure chamber much larger than the opening of the register 3, so that eddy currents will be broken up and a direct and even flow of air into the register will be obtained. By this arrangement the shape and volume of the air stream emanating from the register can be accurately controlled. Either a direct or swirling stream of air may be obtained, and the direction of rotation of the swirling stream caused to be clockwise or counterclockwise by shifting the angle of the vanes 21.

As described, the mixture of oil and air entering the vaporizing chamber has a spiral motion. The large volume of air supplied through the register builds up a pressure within this chamber and envelopes the burning mixture from the gun, retaining it approximately centrally of the combustion chamber.

A rapid mixture of this air with the oil spray may be obtained by turning the radial vanes 21 so that the column of air from the register rotates in a direction opposite to that of the spray to increase the angle of impact of the two. The flame can be lengthened by admitting a direct current of air from the register. By rotating this air column in the same direction as the flame, still further control of the shape of the flame can be obtained.

Since the vaporizing chamber is relatively small, it can be heated within a period of a very few minutes to a temperature which will cause almost instantaneous vaporization of the atomized fuel. This eliminates the necessity of continuous heating and permits closing down the burner when the drier or furnace is not in use. Further, by using a comparatively small chamber, a source of radiant heat is brought close to the stream of atomized oil. Thus the radiant heat in close proximity causes rapid and complete vaporization of the oil while suspended in the air. Likewise, due to the limited size of the vaporizing chamber and large volume of air introduced therein and expansion of the vaporized oil, a pressure is built up, forming an envelope of air about the oil stream, which retards the movement of the oil globules out from the atomizing air stream and prevents their contact with the walls of the vaporizing chamber.

Further, the surrounding envelope is heated and mixes readily with the vaporized oil.

A burning and well mixed volume of gas from the oil and air, surrounded by a large quantity of preheated air is obtained in this manner. The pressure of the mixture is transformed into velocity by the contracted nozzle of the chamber.

I now direct the burning gases and the enveloping air into any furnace or apparatus in which it is desired to use it. I do this by providing at the entrance of the combustion chamber of the furnace or drier a fire tube 7 of greater diameter than the nozzle 6, having at its entrance end a suitable bell 41 with an inner contour substantially complementary to the conelike head 5 of the vaporizing chamber. The fire tube shown as circular in cross section, may be of any desired shape, depending upon whether a column or flattened sheet of flame is desired. This arrangement forms an air passage 42 between the combustion chamber and the bell through which additional air may be drawn into the fire tube and combustion chamber of the furnace.

This air prevents overheating of the fire tube and the combustion chamber of the furnace adjacent to the discharge end of the nozzle, and re-

tains the flame in a position spaced from the walls of the combustion chamber. The heat thus removed is recuperated as the air thus heated unites more rapidly with the gases and insures 5 complete and efficient combustion of the fuel and gases while in the furnace combustion chamber.

The air thus drawn in also forms a second surrounding envelope of air and prevents the 10 gases or any suspended oil therein from coming into contact with the walls of the combustion chamber of the furnace.

Due to the pressure and swirling motion in the vaporizing chamber, the gases and mixture 15 passing therefrom form into a spinning column of flame, the shape of which can be accurately controlled. This flame and mixture being composed of light gases, retains its shape and position near the axis of the column of indrawn air, which likewise 20 has a spiral motion, due to the action of the gases as above described. Radial vanes, which may be in form and function similar to those in the register, may be provided within the annular opening to control the direction of rotation of 25 this air stream, and consequently the shape of flame.

The vaporizing chamber may be moved axially or offset from the axis of the fire tube and bell, so as to change the size and shape of the opening 30 between the bell 41 and conelike head of the vaporizing chamber, thus controlling the amount of air admitted, and the direction and location of the flame.

In order to obtain these positions the legs of 35 the vaporizing chamber may be made in sections such as 48 and 49, and connected by adjusting screws 50. Each of the legs may be provided with a suitable bearing plate such as 52 preferably resting on the floor but not attached thereto, 40 so that lateral movement of the vaporizing chamber is possible. It should be noted that the fuel and air feed lines 16, 32 and 19 are provided with flexible connections to permit such changes in position of the vaporizing chamber.

To preheat the oil when the apparatus is 45 started, I provide an electric heating coil 45 about a portion of the oil feed conduit. Since preheating is at all times desirable, I may provide several turns of the oil feed conduit about the vaporizing 50 chamber as at 46, enclosing the coil in a suitable housing 47. As soon as the vaporizing chamber is heated, the oil passing through the coil of conduit will be heated sufficiently so that the electric coil may be closed down.

It should be noted in this connection that while 55 I have described my apparatus as utilizing air for various purposes, a combustible gas may be used for part or all of the purposes mentioned as to air and will produce very satisfactory results economically.

Experience has proven that without varying the size of the vaporizing chamber or any of the parts of the apparatus, efficient combustion of 60 very heavy crude oil or tars in quantities of from 15 to 140 gallons per hour may be obtained, although a greater range is possible. While for purposes of illustration, I have described my invention in connection with the burning of liquid fuels, it may also be applied to other fuels that 65 are capable of being reduced to small particles, and the invention is so claimed. Again it should be noted that by specifying air in the claims, I means to include any combustion sustaining gas as an equivalent and have used the term "air" 70 for brevity.

Thus I have effected a marked reduction in the cost of heating and have accomplished the objects above set forth.

I claim:

1. An apparatus for burning fuels, including a refractory chamber, a fuel gun in one end of said chamber, means for discharging a stream of small fuel particles and air through said gun into said chamber, said chamber being heated interiorly by combustion of said fuel and thereby providing a source of radiant heat in said chamber for heating and rapidly vaporizing and igniting said fuel, means at the said end of said chamber operable independently of the first named means for blowing a stream of air past the gun into said chamber coaxial with the stream of fuel and air discharged by the gun, said chamber being contracted toward the discharge end for discharging the mixture of fuel and air therefrom at relatively high velocity to points of application, means to vary the shape of the stream of products discharged into said refractory chamber. 80

2. An apparatus for burning fuels, including a refractory chamber, a fuel gun for discharging a stream of small fuel particles into said chamber, means for blowing air through said gun into said chamber, said chamber being heated interiorly by combustion of said fuel and thereby providing a source of radiant heat in said chamber for heating and vaporizing and igniting the fuel during its passage through said chamber, means for forcing air into said chamber around the fuel gun in spaced relation to the walls of the chamber, said means being operable independently of the first named means, and said chamber being contracted at the discharge end to form a nozzle for discharging air and fuel therefrom at relatively high velocity into a port, said port being flared around and spaced from said nozzle to form an annular passage whereby additional air is induced about said burning stream discharged from said chamber and the walls of said port are protected from excessive heat. 100

3. An apparatus for burning fuels, including a circumferentially closed vaporizing chamber, a fuel gun adapted for discharging a stream of fuel particles and air into said chamber coaxial therewith, an air register opening into said chamber around said gun, means for blowing air through said register, said chamber being heated interiorly by combustion of said fuel and thereby providing a source of radiant heat in said chamber whereby said fuel may be vaporized and ignited, a contracted discharge nozzle at the end of said chamber opposite the fuel gun, said nozzle discharging into a port, said port being flared around and spaced from said nozzle and forming a passage for air therebetween and means to regulate the flow of air through said passage. 110

4. An apparatus for burning fuels, including a circumferentially closed chamber, a fuel gun arranged at one end of the chamber and adapted to discharge a stream of fuel particles and air into said chamber, means to blow an additional stream of air into said chamber coaxial with said gun and at predetermined pressure above atmospheric pressure, said means being operable independently of the passage of air into and through said gun, said chamber being heated interiorly by combustion of said fuel and thereby providing a source of radiant heat in said chamber to vaporize and ignite said fuel, said chamber being contracted toward the discharge end and having a discharge opening coaxial with the gun 125 at the opposite end of the chamber therefrom, 130

- whereby the pressure of said air is transformed into velocity and products from said chamber are discharged as a rapidly moving burning stream, a port communicating with said nozzle and discharging into a combustion chamber, means for introducing additional air into said products discharged from said vaporizing chamber after said products are discharged from said chamber.
5. An apparatus for burning fuels, including a refractory vaporizing chamber, a fuel gun adapted for discharging a stream of fuel particles and air into said chamber at one end, an air register communicating with said chamber around the gun, an even pressure chamber communicating with said register, means to blow air under predetermined pressure into said even pressure chamber, whereby eddy currents are reduced and a smooth flow of air into the register is obtained, means to direct the air passing into the chamber through said register to form a swirling annular stream, said chamber being heated interiorly by combustion of said fuel and thereby providing a source of radiant heat within said chamber to vaporize and ignite said fuel, said chamber being contracted at the end opposite the gun to form a nozzle whereby said burning fuel and air may be discharged as a rapidly swirling stream into a combustion chamber.
10. An apparatus for burning fuels, including a refractory chamber, a fuel gun at one end of said chamber adapted for discharging a stream of fuel particles thereinto, means to blow air through said gun, said chamber being heated interiorly by combustion of said fuel and thereby providing a source of radiant heat within said chamber to vaporize and ignite the fuel, an annular air register communicating with said refractory chamber and forming an annular air passage around said fuel gun, means operable independently of the first named means to introduce unagitated air under pressure through said register and into said chamber, said chamber being contracted toward the end opposite the gun to form a restricted discharge opening for discharging said fuel and air therefrom to points of application.
15. An apparatus for burning fuels, comprising a refractory chamber having one end closed by a wall, a fuel gun extending through said wall and adapted for supplying a stream of fuel into said chamber at said end, an annular opening in said wall around said gun, means to supply air through said opening into and about said stream of fuel discharged by the gun, a contracted nozzle on the other end of said chamber coaxial with said fuel stream for passing said fuel and air from said refractory chamber to points of application, a conduit for supplying fuel to said gun, said conduit passing around said refractory chamber in heating relation thereto intermediate a source of supply of fuel and said fuel gun.
20. An apparatus for burning fuels, comprising a precombustion chamber, a fuel gun at one end of said chamber adapted for discharging a stream of fuel particles thereinto, means for blowing air through said gun, a separate additional means for blowing an annular stream of air into said chamber around and coaxial with said gun, said last mentioned means being operable independently of the first mentioned means for controlling independently the flow of air therefrom, said chamber being contracted toward the discharge end and forming a discharge passage coaxial with said gun and at the opposite end of the chamber therefrom for discharging the burning mixture therefrom to points of application.
25. An apparatus for burning fuels, including a refractory vaporizing chamber having a discharge passage at one end, a fuel gun arranged at the other end of said chamber and adapted for discharging thereinto toward the discharge passage, means for forcing air and fuel through said gun into said chamber, means including a spinner coaxial with said gun and operatively associated therewith for effecting a predetermined directional movement of said fuel particles and air as they are discharged from said gun, an air register opening into said chamber around said gun, means for blowing air through said register into said chamber around the stream of fuel and air discharged from said gun, said means being operable independently of the first named means, and said chamber being contracted toward the discharge end and forming a restricted discharge opening coaxial with said gun for discharging the products from said chamber to points of application. 80
30. An apparatus for burning fuels including a refractory precombustion chamber, a fuel gun at one end of said chamber adapted for discharging a stream of fuel particles and air thereinto coaxially of the chamber, said chamber being heated internally by combustion of said fuel and thereby providing a source of radiant heat for heating and rapidly vaporizing and igniting said fuel, an air register in said end of said chamber coaxial with said gun and adapted for discharging air axially of said chamber around and coaxial with the stream of air and fuel discharged from said gun, means for blowing air through said register, said chamber being contracted toward the end opposite from the gun and forming a discharge nozzle coaxial with the gun for discharging said fuel and air from said chamber at relatively high velocity to points of application. 85
35. An apparatus for burning fuels including a refractory precombustion chamber contracted toward one end and having a restricted discharge passage at said contracted end, a fuel gun at the other end of said chamber coaxial with the discharge passage adapted for discharging a stream of fuel particles into said chamber axially thereof toward the discharge passage, blower means for blowing air through said gun, an air register opening around said gun and coaxial therewith and arranged to discharge axially past the gun into said chamber, a conduit communicating with said register, a separate blower means for blowing air through said conduit into and through said register, and means in said conduit for changing the size of the air passage therethrough for controlling the flow of air through the register independently of the flow of air through said gun, and means in said register to impart selected directional movements to the air discharged therethrough into said chamber. 90
40. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 95
45. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 100
50. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 105
55. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 110
60. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 115
65. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 120
70. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 125
75. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 130
80. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 135
85. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 140
90. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 145
95. An apparatus for burning fuel comprising a refractory precombustion chamber contracted toward one end and having a restricted discharge passage at said contracted end, a fuel gun at the other end of said chamber coaxial with the discharge passage and adapted for discharging a stream of fuel particles and air into the chamber axially toward the discharge passage, an annular air register around said gun coaxial therewith and having a discharge opening behind the discharge opening of the gun, means for supplying air 150

through said register axially of said gun into said chamber, and means for controlling the volume of flow of air thruogh said register independently of the flow of air through said gun.

5 13. An apparatus for burning fuels including a refractory precombustion chamber, a fuel gun at one end of said chamber coaxial therewith and adapted for discharging a stream of fuel particles and air thereinto axially of the chamber, said

10 chamber being heated internally by combustion of said fuel and thereby providing a source of radiant heat for heating and rapidly vaporizing and igniting said fuel, an air register in said end of the chamber coaxial with said gun and adapted for discharging air axially of said chamber around and coaxial with the stream of air and

15

fuel discharged from said gun, a spinner in said gun operable consequent upon passage of air therethrough for imparting a predetermined directional movement to said air and fuel particles, means in said register for imparting to the air discharged therethrough into the chamber a directional movement counter to the directional movement of the air discharged by the gun, said chamber being contracted toward the end opposite the gun and having a restricted discharge opening at the contracted end coaxial with the gun for discharging said fuel and air from the chamber at relatively high velocity to points of application.
